Primary Examiner—Wallace R. Burke*Assistant Examiner*—Lavone D. Tabor*Attorney, Agent, or Firm*—Rosenman & Colin**[57]****CLAIM**

The ornamental design for a handle for toothbrushes, as shown and described.

DESCRIPTION

FIG. 1 is a top plan view of a handle for toothbrushes showing my new design;

FIG. 2 is a left side elevational view thereof;

FIG. 3 is a bottom plan view thereof;

FIG. 4 is a right side elevational view thereof;

FIG. 5 is an enlarged sectional view taken along line 5—5 of FIG. 4;

FIG. 6 is a rear end elevational view thereof;

FIG. 7 is a top plan view of a second embodiment of the design shown in FIG. 1;

FIG. 8 is a left side elevational view thereof;

FIG. 9 is a bottom plan view thereof;

FIG. 10 is a right side elevational view thereof;

FIG. 11 is an enlarged sectional view taken along line 11—11 of FIG. 10; and,

FIG. 12 is a rear end elevational view thereof.

The broken lines showing of a toothbrush head and neck and bristles in FIGS. 1-4 and 7-10 are for illustrative purposes only and form no part of the claimed design.
